UNITED STATES PATENT OFFICE

2,474,358

MEANS FOR LAPING TAPER-SIDED SPLIT RINGS

John William Howlett and Arthur J. Woolcott,
Lymington, England, assignors of one-third to
Wellworthy Piston Rings Limited, Lymington,
England.

Application February 3, 1947, Serial No. 726,160
In Great Britain November 24, 1941

Section 1, Public Law 690, August 8, 1946
Patent expires November 24, 1961

6 Claims. (Cl. 51—56)

1

This invention relates to piston-rings, such as are commonly known as taper-sided rings, of the kind of which at least one side face is not in a plane at right-angles to the axis of the ring. This side face is usually in the form of a truncated cone, but instead of being flat it may be convex or concave to a small extent.

It is found in practice that whereas such rings have certain advantages in use, there is a tendency for the ring grooves in the piston to wear at a rather high rate, due, in all probability, to the abrading action of the side face of a ring on the adjacent side face of the groove as the ring expands and contracts in the groove.

It is our main object to prevent this from happening.

A further object is to arrange for the said side face of the ring to be honed or lapped by mechanical means, and preferably the irregularity in the surface finish of the side face should not exceed fifteen micro-inches.

A further object is to provide a mechanical means for honing or lapping a side face of a piston-ring as aforesaid, by which the honing or lapping block is moved circumferentially relatively to the ring, and also oscillated to-and-fro in a more or less radial direction with respect to the ring.

For a better understanding of these and other objects and advantages of the invention attention should be directed to the following description in which reference is made to the accompanying sheets of diagrammatic drawings, wherein—

Figure 1 is a vertical section through one form of mechanical means as aforesaid.

Figure 2 is a sectional plan view taken on the line II—II of Figure 1.

Figure 3 is a fragmentary perspective view and cross-section taken on the line III—III of Figure 2;

Figure 4 is a fragmentary plan view of a portion of the ring and base; and

Figure 5 is a part-sectional elevation of another form of mechanical means as aforesaid.

In the construction of Figures 1 to 4 there is a base built up of a central portion 11 and a surrounding annular portion 12 which are secured to one another in any convenient manner. The upper surface of the central portion is of frusto-conical shape corresponding to the taper of a taper-ring 13 which is to be treated, the ring 13 in this case having a corresponding taper on both sides. The annular portion 12 forms a backing for the ring when placed in position on the central portion, engaging the periphery thereof.

2

as shown by Figures 3 and 4. The ring is held against movement by means of a lug 14 secured as by screws to the annular portion and having a tongue 15 projecting over the central portion into the gap at the ends of the ring, as shown by Figure 4.

The head of the machine comprises a rotatable portion 16 which in this case is shown as being fast with a driving shaft 17 and a stationary annulus 18, the latter being formed with lugs 19 to engage corresponding recesses 21 formed in the rim of the annular base portion 12 when the head is moved into engagement with the base. On the underside of the rotatable portion of the head there are arranged two pairs of slides 23, 24 each of which is of T-shape, as shown by Figure 3, being carried in a T-section slot formed in the head. Each slide carries a block 26, for example, a honing stone, or, as will be well understood, if preferred, the block 26 may be a cast-iron lapping block to act on the surface of the ring through a suitable lapping medium.

The stationary portion 18 carries two superposed cam rings 27, 28 secured as by means of screws 29. The contours of these are substantially similar but angularly staggered. One pair of slides (the pair 23 in this instance) engages the top cam 27, and the other pair of slides 24 engages the bottom cam 28. The slides are held in engagement with the cams by means of a ring 30 disposed loosely round the shaft-end and retained in position by resting upon ledges 31 formed at the radially-inner ends of the slides.

Thus, when the shaft 17 is rotated the slides travelling round the cam surfaces are oscillated radially with respect to the head. The operative surfaces of the block 26 are parallel to the taper of the ring, as are also the slides 23, 24. The arrangement is such, it will be observed, that the operative surface of the ring can be very accurately honed, the honing stones of the slides 23 overlapping in their travel the path of travel of the honing stones in the slides 24. In point of fact, we arrange for the regularity in the surface finish not to exceed fifteen micro-inches and preferably to be less.

For rings having a different taper of a side face it will be obvious that a different base centre 11 will be required for the support of the ring and a different head centre 16 in order that the movement of the slides shall be in directions parallel to the adjacent side face of the ring. Alternatively, as will be well understood, the slides may be mounted in parts which are adjustable in the head for this purpose.

It will also be evident that the number of slides to be used or the number of cam rings can be varied as required. Furthermore, if preferred, the shaft 17 may be held stationary and the base (and with it the cam ring) rotated.

In the construction shown by Figure 5 there is a stationary base 33 in which is journalled a rotatable base 34 carrying the piston-ring 35 which is to be treated. The rotatable base is formed with a stem portion 37 having worm teeth 38 thereon engaged by a worm 39. Rotation of the worm 39 therefore serves for rotating the rotatable base.

The head 41 is in this case stationary, being formed with eyes which slidably receive guiding rods 42 fast with the stationary base, but journalled in the head are four sleeves 44 in which are eccentrically mounted four pins 45. The upper ends of the pins are interconnected by a plate 46 whereby the pins are held against rotation, and at their lower ends are mounted honing stones or lapping blocks 47. As shown in the figure, a block 41 may be mounted in a holder 48 which is dowelled at 49 to the associated pin 45 and is retained in position by a nut 51. The upper ends of the sleeves carry gear wheels 52, all of which are in mesh with a central gear wheel 53 fast on a driving shaft 54, the latter extending through a clearance hole in the plate 46.

In consequence the rotation of the driving shaft will rotate the sleeves 44 and thereby effect oscillation of the pins 45 in a more or less radial direction with respect to the ring 35, carrying the honing or lapping blocks across the surface of the ring while the latter is being rotated by the rotatable base.

If desired, the sleeves 44 may be adjustably supported in the rotational portion of the head, their gear wheels 52 being connected with the driving gear wheel 53 through idle gears whereby to allow of the adjustment of the pins 45 according to the size and shape of a ring to be treated.

In like manner it will be understood that in either of the constructions described, if it be desired to hone or lap a ring which is slightly convex or slightly concave, the slides 23, 24 in the first example, and the pins 45 in the second example, must be mounted to provide the necessary movement.

It is desirable that the honing or lapping exerted by the head on the ring should not be less than 20, or more than 150, pounds per square inch.

What we claim as our invention and desire to secure by Letters Patent of the United States is:

1. A mechanical means, for honing or lapping a side face of a taper-sided split piston ring, including a base adapted to support the ring, means fast with the base for engaging in the split of the ring for preventing relative rotation between said ring and said base, a head carrying a slide, the slide supporting a honing or lapping block in contact with the appropriate side face of the ring, means for effecting relative rotation of the head and base, and cam means coacting with the slide so as to oscillate the latter during such relative rotation, the slide and honing or lapping block being mounted so that the oscillatory movement of the said block will be parallel to the taper of the side face of the ring.

2. A mechanical means, for honing or lapping a side face of a taper-sided split piston ring, including a stationary base adapted to support the ring, means fast with the base for engaging in

the split of the ring for preventing relative rotation between said ring and said base, a rotary head, an annular member rotatively carried by said head, interengaging teeth of said stationary base and annular member for preventing rotation of the latter, a slide carried by said head, the slide supporting a honing or lapping block in contact with the appropriate side face of the ring, means for effecting relative rotation of the head and base, and cam means which are carried by said annular member and which coact with the slide so as to oscillate the latter during such relative rotation, the slide and honing or lapping block being mounted so that the oscillatory movement of the said block will conform to the shape of the side face of the ring.

3. A mechanical means, for honing or lapping a side face of a taper-sided split piston ring, including a base adapted to support the ring, means fast with the base for engaging in the split of the ring for preventing relative rotation between said ring and said base, a head carrying a slide, the slide supporting a honing or lapping block in contact with the appropriate side face of the ring, means for effecting relative rotation of the head and base, annular cam means coacting with the radially outer end of the slide, and means for biassing said slide for its said outer end to maintain contact with said annular cam means so that said slide is oscillated during such relative rotation, the slide and honing or lapping block being mounted so that the oscillatory movement of the said block will conform to the shape of the side face of the ring.

4. A mechanical means, for honing or lapping a side face of a taper-sided split piston ring, including a base adapted to support the ring, means fast with the base for engaging in the split of the ring for preventing relative rotation between said ring and said base, a head carrying a plurality of radially arranged slides, each said slide supporting a honing or lapping block in contact with the appropriate side face of the ring, means for effecting relative rotation of the head and base, a plurality of annular cam means with wavy contours respectively engaged by the outer ends of different slides, and means for biassing said slides for their said outer ends to maintain contact with said annular cam means so that said slides are oscillated during said relative rotation, the slides and honing or lapping blocks being mounted so that the oscillatory movement of the said blocks will conform to the shape of the side face of the ring.

5. A mechanical means, according to claim 4, of which the means for biassing the slides is a loosely supported ring of which the outer periphery bears on the inner ends of said slides.

6. A mechanical means, for honing or lapping a side face of a taper-sided split piston ring, including a base adapted to support the ring, means fast with the base for engaging in the split of the ring for preventing relative rotation between said ring and said base, a head carrying a plurality of slides arranged radially in aligned pairs, each said slide supporting a honing or lapping block in contact with the appropriate side face of the ring, means for effecting relative rotation of the head and base, a plurality of superposed annular cam means with wavy contours respectively engaged by the outer ends of a said pair of slides, the cam means being orientated to stagger their respective wavy contours, and means for biassing said slides for their said outer ends to maintain contact with the coacting annular cam means so

that the said slides are oscillated during said relative rotation, the slides and honing or lapping blocks being mounted so that the oscillatory movement of the said blocks will conform to the shape of the side face of the ring.
